Patented Sept. 24, 1912.

UNITED STATES PATENT OFFICE.

GEORGE E. TOMS AND THOMAS P. BLAIR, OF SAN DIEGO, CALIFORNIA, ASSIGNORS OF
ONE-THIRD TO SIGMUND FREY, OF LOS ANGELES, CALIFORNIA.

GRAVITY-HINGE.

1,039,216.

Specification of Letters Patent. Patented Sept. 24, 1912.

Application filed May 10, 1912. Serial No. 696,404.

To all whom it may concern:

Be it known that we, GEORGE E. TOMS and THOMAS P. BLAIR, of San Diego, in the county of San Diego and State of California, 5 have invented an Improved Gravity-Hinge, of which the following is a specification.

This invention has reference to improvements in gravity hinges which are adapted to pivotally connect relatively movable objects, as a door or gate, to a fixed or stationary support, comprising the arrangement of parts and operating devices with the herein described features and advantages, which will cause the door or gate, upon 15 opening, to be slightly raised to clear the floor or other obstructions, and, when fully opened, to remain in position until started in a closing movement, whereupon said operating devices will be actuated by gravity 20 and by the weight of the door or gate, to completely close the same.

While the elements shown and described are well adapted to serve the purposes and accomplish the objects of the invention, no 25 limitation is made to the precise structural details herein exhibited, but variations, alterations, and modifications, that conform to and are included within the scope of the 30 claims, may be made to meet the requirements in compliance with advantages of operation, the essence of our invention comprising pivotally associated, companion hinge leaves, having integral and corresponding knuckle parts, a recess being be- 35 tween certain of the adjacent knuckles, lugs in said recess, lifting collars attached to said lugs, and a pintle uniting the co-acting parts, a preferred form of the invention being shown in the accompanying drawings, 40 whereon—

Figure 1 is a side elevation of a hinge embodying our invention, disclosing the parts in open position, Fig. 2 is a side elevation of the hinge in closed position, Fig. 45 3 is a rear edge view of the hinge in closed position, Fig. 4 is a plan view of the hinge leaves with pintle and operating members removed, Fig. 5 is a detail view of the pintle with cap removed, and Fig. 6 is a perspective view of an operating member showing the slot for securing to a lug on a hinge leaf.

In the several figures, like reference characters apply to like parts.

Assuming the invention to be embodied in 55 the form illustrated, members 1 and 2 com-

prise the companion plates or leaves, of which leaf 1 is provided on its inner edge with a longitudinally arranged knuckle 3, and adjacent thereto, an elongated lug 4, projecting toward the axis of the knuckle. 60 Leaf 2 is provided with a short knuckle 5, and a longer knuckle 6, longitudinally arranged upon the inner edge and at opposite ends of the leaf, and therebetween, an elongated lug 7. Knuckles 3, 5, and 6, are 65 formed for the insertion of pintle 8, which has a reduced and threaded end 9, and a cap 10 screwed thereon, the companion hinge leaves being secured by and pivotally movable upon pintle 8. With said companion 70 leaves mounted in their relative positions, a recess 10 is formed between adjacent knuckles, and companion collars 11 and 12 are mounted therein, said collars having longitudinal slots 13, for engaging with lugs 75 4 and 7, which cause said collars to be turned by and in unison with said leaves, and having parts of their engaged ends inclined, forming cams 14 and 15 which are in co- 80 operative engagement during the opening and closing of the hinge, causing the hinge leaves to have a longitudinal movement relative to one another. Tapered projections 16 and 17, respectively, on the inner ends of knuckles 3 and 6, set into corresponding 85 sockets in the outer ends of actuating collars 11 and 12, thereby bracing and maintaining alinement of the parts.

From the foregoing it may be seen that we have provided a hinge in which the 90 leaves may be stamped from sheet metal, and in which lifting parts are provided which coöperate to effect a complete closure of the hinge, except when open to the full extent, which will lift the door or gate supported thereby to clear obstructions during the opening and closing thereof, and which will permit the same to rest upon the floor or sill in the closed position. Short flat faces adjoining said cams on the actuating 95 collars, will cause the door or gate to remain open until swung back sufficiently to bring said cams into engagement, whereupon the weight of the door or gate will force the cam upon one collar to slide upon the cam of the other collar, thereby bringing the door or gate to a closed position.

We claim as our invention:

1. In a gravity hinge, a pair of companion hinge leaves, coöoperating knuckles on 110

their adjacent edges arranged to form a recess therebetween when said leaves are assembled in their relative positions, a pintle adapted for insertion in said knuckles to 5 hingedly and slidably connect said leaves, lugs on the inner edges of said leaves projecting in said recess, collars pivotally mounted on said pintle within said recess, and provided with longitudinal slots for engagement with said lugs, and cam faces on 10 said collars co-acting to shift said leaves longitudinally upon said pintle when said leaves are turned, substantially as set forth.

2. In a gravity hinge, a pair of companion hinge leaves, coöperating knuckles on the 15 adjacent edges of said leaves arranged to form a recess therebetween when said leaves are assembled, collars mounted in said recess, a pintle adapted for insertion in said leaves and collars to slidably and pivotally

connect the same, lugs on said leaves engaging with said collars whereby the collars are rotated in unison with said leaves, inclined co-acting faces on the inner ends of said collars to move the hinge leaves longitudinally 25 relative each to the other when the same are rotated, and tapered projections on the inner ends of said knuckles engaging with said collars to strengthen and brace the same when co-acting to operate said hinge leaves, 30 substantially as set forth.

In testimony whereof we have hereunto affixed our signatures to the foregoing specification, this 29th day of April, 1912.

GEORGE E. TOMS.
THOMAS P. BLAIR.
